Patented Aug. 18, 1914

UNITED STATES PATENT OFFICE.

WILLIAM KENNEDY MASON, OF CAMBRIDGE, MASSACHUSETTS, ASSIGNOR TO JOHN W. BURNETT, OF CAMBRIDGE, MASSACHUSETTS.

ELECTRIC DRYING APPARATUS.

1,107,814.

Specification of Letters Patent. Patented Aug. 18, 1914.

Application filed April 28, 1914. Serial No. 834,942.

To all whom it may concern:

Be it known that I, WILLIAM KENNEDY MASON, a citizen of the United States, and resident of Cambridge, in the county of 5 Middlesex and State of Massachusetts, have invented certain new and useful Improvements in Electric Drying Apparatus, of which the following is a specification.

This invention relates to electrically 10 heated apparatus for drying purposes, and particularly to apparatus for drying the human scalp and the hair thereon.

The invention has for its object to enable the temperature of the heat-applying 15 part or applicator of an electrically heated drying apparatus to be automatically maintained at substantially a predetermined degree, and to prevent the possibility of burning the object or objects being dried.

20 The invention consists in the improvements which I will now proceed to describe and claim.

Of the accompanying drawings forming a part of this specification; Figure 1 represents a side elevation of a hair and scalp 25 drying apparatus embodying my invention; Fig. 2 represents a side elevation of the same, partly in section; Fig. 3 represents a section on line 3—3 of Fig. 2; Fig. 4 represents an enlarged longitudinal section of the thermostatic arm hereinafter referred to.

The same reference characters indicate the same or similar parts in all the views.

The drying apparatus here shown for purposes of illustration comprises an electrical heating unit which includes a resistance coil 12 of wire helically wound on a core 13 and included in an electric circuit which also includes circuit wire portions 14 and 40 15 connected with opposite ends of the coil 12, and a circuit wire 16. The core 13 is preferably a tube of asbestos or mica supported by an inner tube 13^a of metal, the tube 13 insulating the coil 12 from the 45 inner tube 13^a. The wires 14 and 16 may extend through a handle 17, the wire 16 being connected with a fixed contact member 18.

19 represents a thermostatic circuit breaking and closing member or arm which is an electrical conductor connected with the wire 15, said arm being composed of two or more metal layers having different coefficients of expansion and contraction. The arm 19 is

therefore adapted to be deflected by an increase of temperature and separated from the member 18 to break the circuit and to be returned to its normal shape by cooling to again make contact with the member 18.

The heating unit is inclosed in a tubular 60 heat conducting holder 21 from which it is insulated by a lining tube 22 of asbestos, which not only insulates the coil 12 from the holder 21, but also serves to store, and diffuse, or uniformly distribute the heat therefrom, and prevent the coil 12 and the core which supports it from rattling in the holder, the asbestos lining being compressible and constituting a yielding packing. Projecting from the holder 21 is a heat-conducting extension which as here shown is composed of spaced flanges 23 of heat-conducting material, the circuit controlling members 18 and 19 being secured to one of said flanges by suitable fastenings, such as 70 screws 24, as shown by Fig. 2. Said flanges constitute a socket or coupling member to engage the applicator next described.

25 represents a comb-shaped applicator of heat-conducting material, preferably aluminum. The back of said applicator is formed to have a close frictional fit between the flanges 23, so that the applicator is detachably connected with the heating portion of the apparatus and may be conveniently removed to be cleaned and sterilized.

When the circuit is closed by contact of the members 18 and 19 with each other, the holder 21 is heated by the coil 12, and heat is conducted therefrom through the flanges 90 23 to the applicator. When the temperature of the socket rises above a predetermined degree the circuit is broken by the expansion of the thermostatic arm or member 19 until the temperature is sufficiently lowered. Provision is therefore made for automatically regulating the temperature of the applicator and maintaining it at a substantially uniform degree so that liability of burning the subject operated on by the 95 drier is prevented.

It will be seen that the automatic circuit controller composed of the members 18 and 19 is located on the heat-conducting extension and between the heating unit and the 105 applicator and in close proximity to the latter, so that the applicator is kept at substantially the same temperature as the ex-

5 tension or socket. This arrangement is important, because it insures a suitable temperature of the applicator at all times, and prevents the applicator from cooling below the requisite drying temperature.

10 The holder 21 is preferably incased in a tubular sheath 30 of a material which is a poor conductor of heat. Said sheath may be integral with the handle 17. Said handle may be omitted, however, if desired.

15 In Fig. 2 I have shown diagrammatically a source of electrical energy 31, and connections between it and the wires 16 and 17. Said connections may include plugs insertible in sockets 32 at the outer end of the handle 17. The thermostatic arm 19 may be adjusted by a bearing screw 33 engaged with a base plate 34 to which the arm 19 is attached by screws 35.

20 It is obvious that my invention may be embodied in an apparatus having an electrical heating unit of different construction from that here shown, and that the applicator may be permanently secured to the heat-conducting extension instead of being detachable therefrom.

The members 18 and 19 are protected by a cover 36.

Having described my invention, I claim:

30 1. A drier of the character stated, comprising an electrical heating unit, including a heating circuit, a tubular heat-conducting holder inclosing said unit and having a laterally projecting extension to conduct heat therefrom, a thermostatic circuit controller carried by said extension and adapted to automatically regulate the temperature thereof, and a comb-shaped heat-conducting applicator having a back in contact with said extension to conduct heat

therefrom, said back being in close proximity to the circuit controller.

2. A drier of the character stated, comprising an electrical heating unit, including a heating circuit, a heat-conducting holder 45 connected with said unit to conduct heat therefrom, said holder being provided with a heat-conducting extension formed as a coupling member, a thermostatic circuit controller carried by said extension and 50 adapted to automatically regulate the temperature thereof, and a comb-shaped heat-conducting applicator having a complementary coupling member formed to detachably engage said extension and held thereby in close proximity to said circuit controller.

3. A drier of the character stated, comprising an electrical heating unit including a resistance coil and an insulating core therein, a tubular heat-conducting holder 60 inclosing said coil and having a lining of insulating and heat-diffusing compressible material, adapted to prevent rattling of the coil and core in the holder, and a laterally projecting extension to conduct heat from 65 the holder, a thermostatic circuit controller carried by said extension and adapted to automatically regulate the temperature thereof, and a comb-shaped heat-conducting applicator having a back in contact with 70 said extension to conduct heat therefrom, said back being in close proximity to the circuit controller.

In testimony whereof I have affixed my signature, in presence of two witnesses.

WILLIAM KENNEDY MASON.
